T. F. CHEEK

CABINET PLAYER

Filed Sept. 20, 1923

UNITED STATES PATENT OFFICE.

TOLBERT F. CHEEK, OF NEW YORK, N. Y., ASSIGNOR TO WELTE-MIGNON CORPORATION,
OF NEW YORK, N. Y., A CORPORATION OF NEW YORK.

CABINET PLAYER.

Application filed September 20, 1923. Serial No. 663,830.

To all whom it may concern:

Be it known that I, TOLBERT F. CHEEK, a citizen of the United States, residing at New York city, in the county of Bronx and State of New York, have invented certain new and useful Improvements in Cabinet Players, of which the following is a specification.

This invention relates to that type of record controlled piano playing mechanisms (hereinafter called "cabinet piano players") in which the player mechanism is mounted within a casing or cabinet formed separate from the piano and is placed immediately in front of the piano when in use thereon and is movable away from the piano when the latter is to be played by hand. In this type of mechanism, there are a series of fingers or levers which project rearwardly from the case or cabinet into engagement with the piano-keys, respectively, when the player mechanism is in operative relation with the piano, and it is a particular purpose of the present invention to provide an improved correlation of parts whereby these fingers or levers (hereinafter called "key-operating-levers") may be expeditiously and conveniently withdrawn to within the confines of the cabinet, permitting the back of the latter to be closed and to be set up against a wall of the room, when the player is not in use, and wherein also the parts are so arranged that the cabinet may present a most pleasing appearance, in no wise suggestive of the ordinary cabinet piano player. In a companion application executed by me, and filed in the United States Patent Office of even date herewith and designated "Case A", the said application bearing Serial Number 663,829, I have set forth and described a form of invention in which, among other things, provision is made for the complete withdrawal of the key-operating-levers to within the confines of the cabinet without enlarging the depth of the cabinet to receive said levers. In the form shown in said companion application, as well as in the present embodiment of the invention, this is effected by mounting the key-operating-levers upon a rail or carrier which has movement such that the key-operating-levers are movable bodily forward and rearward relatively to the casing. This generic feature is broadly claimed in my said companion application (Case A) and to that extent the

present invention is subsidiary. In the particular embodiment set forth in my companion application the particular member of the structure to which the several key-operating-levers is attached is pivoted so as to swing relatively to the casing in withdrawing said levers from their outer (operative) position to their storage position within the confines of the casing, or in moving them from their said storage to their operative position: and the present embodiment of the invention differs therefrom in that the parts are so correlated that while the movement of the key-operating-levers is a bodily one it is brought about by means of a slideable carrier or rail, instead of by a pivoted carrier or rail.

In the accompanying drawing wherein like characters of reference denote corresponding parts in the several views:—

Fig. 1 is a side view, partly in section, of the forward part of a grand piano, and a like view of a cabinet player in operative relation therewith, with a part of an end wall of the cabinet broken away to disclose certain parts of the player mechanism therein, and with parts of said player mechanism and a part of the rear wall of the cabinet in section,

Fig. 2 is a rear elevation of the cabinet, with the key-operating-levers in section: and

Fig. 3 is a detail view in perspective of the member which carries the several key-operating-levers for striking the keys.

A designates the case of a cabinet player. This case may be of any suitable construction, but as here shown it has a flat top *a* beneath which, in the upper portion of the case, a compartment having a suitable hinged closure for giving access thereto is provided for the tracker bar 10 and the feed and rewind rolls 11, 12. From the tracker bar 10 several ducts, one of which is shown and marked 13, extends to the pneumatic mechanism for operating the player. This pneumatic mechanism preferably includes a striker pneumatic unit 14 which supports and controls the several striker pneumatics 15 and 16 which are shown as being in rows and in a staggered relation, the pneumatics 15 of one row respectively controlling the operations of the levers 25 which operate the white keys of the piano while the pneumatics 16 of the other row respectively control the operations of the levers 26 which operate the

black keys of the piano. The illustrated pneumatics are of bellows form and the movable board of each has an arm of which those (marked 17) connected to the pneumatics 15 have their upper ends operatively engaged with the inner ends of the key levers 25 and those (marked 18) connected to the pneumatics 16 have their upper ends operatively engaged with the inner ends of the key levers 26. These arms are pivotally connected at their lower ends to the movable board of the striker pneumatics, respectively, and all of them extend through openings in a guiding member 20 suitably supported in proper position within the cabinet.

Suitably fixed to the inner surfaces of the opposite end walls a' of the cabinet are guiding and supporting members marked 21 and 22, respectively. These members extend toward the front of the cabinet from the rear wall a^2 and are provided with longitudinal openings 23 and 23'. They are arranged in a compartment of the cabinet below the upper compartment and above the plane of the pneumatics 15 and 16. 24 designates a member which is slidably mounted in the cabinet with its ends operatively related to the members 21 and 22, respectively, so as to be supported and guided thereby. This member 24 supports and carries the entire series of key-operating-levers 25 and 26, each of which is pivotally connected therewith between its ends. To provide for said pivotal connection of the key-operating-levers with the member 24, the latter is provided with arms 27 to which the key-operating-levers 25 are pivoted and arms 28 to which the key-operating-levers 26 are pivoted. All of these arms depend from the member 24 and have their upper ends fixedly secured to said member.

The length of the slots 23 and 23' is so related to the length of the key-operating-levers 25 and 26 that when the supporting and carrying member 24 has been moved to its outer position the outer ends of the key-operating-levers will protrude through an opening 34 in the rear wall of the casing and the inner ends of said levers will be in operative relation with the corresponding arms 17 and 18; and when said member 24 has been moved to its inner position the key-operating-levers 25 and 26 will be withdrawn entirely within the cabinet. These slots 23 and 23' have their forward and rear ends spaced from the ends of the members 21 and 22 to provide stop walls 30 at their forward and rear ends to define the extent of in and out movements of the members 21 and 22 and key-operating-levers.

As shown in Fig. 3, the member 24 has its opposite ends provided with projecting fingers 31 to enter the slots 23 and 23' and one of the longitudinal edges of said member is provided with beads 32 and 33 arranged

one above the other. The lower beads forms a projecting ledge which enters recesses in the arms 27 to which the key-operating-levers 25 are pivoted, and the upper bead 33 similarly forms a projecting ledge which enters recesses in the arms 28 to which the key-operating-levers 26 are pivoted, these beads and the recesses in the several arms thereby co-operating with each other to guide the assembler in aligning the arms as well as tending to hold the arms against accidental vertical displacement while permitting lateral adjustment of the arms with the key-operating-levers to properly position said levers with relation to the arms 17 and 18. Any appropriate fastening means may be used if necessary to further secure the arms to the member 24. The opening 34 in the rear wall of the cabinet gives access to the member 24 and to the interior of the cabinet and a door 35 is arranged to cover this opening when the key-operating-levers have been moved to their storage position within the confines of the cabinet.

It will be noted that inasmuch as the key-operating-levers can be moved as a unit inward and outward with relation to the cabinet by the mere operation of similarly moving a slidable member common thereto, the operation of adjusting the key-operating-levers so that they will be out of the way when not in use is expedited.

It will be obvious that while I have described and illustrated what I regard as the preferred form of my invention yet changes in the details may be made without departing from the spirit of the invention or the scope of the appended claims.

It is considered to be unnecessary to describe or illustrate herein those parts of the player mechanism which produce the necessary air tensions within the mechanism, or which operate or control the operation of the record and striker pneumatics under control of said air tensions, for the reason that these parts form no essential part of the present invention, as any suitable means, several of which are known in the art, may be employed for these purposes.

Having thus described the invention, what I believe to be new and desire to secure by Letters Patent, is:—

1. A cabinet piano player comprising a casing and a series of key-operating-levers slidably mounted to move bodily inward or outward with relation to the casing.

2. In a cabinet piano player, the combination with the casing thereof, of a series of key-operating-levers and means which carries the key-operating-levers and is slidably mounted to move the same bodily inward or outward with relation to the casing.

3. In a cabinet piano player, the combination with the casing thereof, and a series of strike pneumatics, of a series of key-

operating-levers to be operated by the strike pneumatics, respectively, and a carrying member common to the key-operating-levers and to which said levers are pivoted, mounted to move slidably in the casing to carry the key-operating-levers bodily inward or outward relatively to the casing and strike pneumatics.

4. A cabinet piano player, comprising a casing having an opening, strike pneumatics in the casing, a series of key-operating-levers to be operated by the strike pneumatics, respectively, and a common carrying member for the key-operating-levers mounted to be slid in paths which are defined as to direction and extent, the slidable movement of said member in one direction positioning the key-operating-levers into operative relation with the strike pneumatics and with their ends projecting through the opening in the casing to operate upon the piano keys and in another direction within the casing disconnecting the key-operating-levers from the strike pneumatics and arranging them entirely within the confines of the casing.

5. A cabinet piano player comprising a casing, members attached to the opposite end walls of the casing and each provided with a longitudinal slot which terminates short of its opposite ends, to provide stops at the ends of the slot, a member having projections which engage and traverse said slots, and a series of key-operating-levers pivoted between their ends to the latter member and carried bodily thereby inward and outward relatively to the casing.

6. A cabinet piano player comprising a casing, strike pneumatics in said casing, slotted members in the casing fixedly connected to opposite walls thereof and having stops at the ends of their slots, a slidable member arranged above the plane of the strike pneumatics and whose ends engage said slots and traverse the same, a series of key-operating-levers arranged between the planes of the strike pneumatics and slotted members and pivotally connected to the slidable member so as to be movable pivotally relatively thereto and bodily therewith, and operating connections between the strike pneumatics and the key-operating-levers, respectively, to operate said key levers pivotally when the key-operating-levers are in their outer positions.

7. A cabinet piano player comprising a casing, rows of strike pneumatics, supporting and guiding members attached to opposite walls of the casing above the plane of the strike pneumatics, a slidable member supported by said members and having longitudinal ribs in different horizontal planes, rows of fixed arms depending from said slidable member and having recesses to receive said ribs, respectively, a series of key-operating-levers, pivoted between their ends to the arms of one row, respectively, connections by which said levers are operated by the pneumatics of one row respectively, a second series of key-operating-levers, pivoted between their ends to the arms of the other row, respectively, and connections by which the second series of key-operating-levers are operated by the pneumatics of the other row, respectively.

8. A cabinet piano player, comprising a casing, strike pneumatics, having movable boards, arms pivotally connected to said movable boards to be operated thereby, guiding means for said arms, a slidable member above the strike pneumatics, and key-operating-levers pivotally connected between their ends to said slidable member and movable bodily therewith inward or outward relatively to the case and strike pneumatics, said levers when in their outer position having their inner ends in operative relation with the arms of the strike pneumatics, respectively, to be operated thereby.

9. A cabinet piano player, comprising a casing, a tracker bar, striker pneumatics, suitable connections between the striker pneumatics and the tracker bar, supporting and guiding members above the plane of the striker pneumatics, a slidable member whose ends traverse the supporting and guiding members, a series of key-operating-levers above the striker pneumatics and pivotally connected between their ends to the slidable member to be movable pivotally relatively thereto and bodily inward and outward therewith, and operating connections between the striker pneumatics and the key-operating-levers, respectively, to operate said key-operating-levers pivotally when the key levers are in their outer position.

In testimony whereof I affix my signature.
TOLBERT F. CHEEK.
